DEVICE FOR SUPPORTING PACKAGES OF STRAND MATERIALS

Barend van den Bergh, Ginneken, Netherlands,
assignor to American Enka Corporation, Enka,
N. C., a corporation of Delaware

Application August 22, 1938, Serial No. 226,166
In Germany September 3, 1937

1 Claim. (Cl. 242—130)

The present invention relates to a device for supporting packages of strand material, and more particularly, to the provision of an adjustable stand on which a cone or similar yarn package may be mounted for subsequent unwinding operations.

In the manufacture of synthetic or natural yarns the finished product is usually wound into the form of conical packages suitable for the 10 production of fabrics. These cones are placed on knitting or weaving machines in an upright position so that the yarn may be unwound properly. However, the entire yarn body must be disposed in a manner to permit uninterrupted 15 unwinding and care must be exercised that the yarn does not become entangled or entrapped beneath the cone, in which case breakage and consequent shutting down of the machines would result.

20 The cone consists of a body of yarn wound onto a hollow core made of appropriate fibrous material such as stiff paper or cardboard. In order to position or "set up" the cone on a knitting machine, the cone is placed upright upon a support comprising a flat surface to accommodate the base of the body of yarn. During the operation of the machine the package remains stationary. Inasmuch as the yarn is so wound on the conical core as to occupy only a portion of 25 its length, the core projects beyond the body of yarn at the bottom and top. Since the base portion of the conical core extends below the base of the body of yarn, an opening is usually provided in the support to receive the projecting lower end of the core to permit the body of yarn 30 to rest upon the support.

As stated before, in supplying the yarn to knitting machines, it is drawn upward from the top of the cone in so-called "over-end delivery" and 40 during the unwinding procedure numerous difficulties have been encountered. This is due to the fact that the weight of the yarn body, resting upon its support, causes delivery of the coils of yarn between the base of the yarn body and its 45 support to be retarded due to the yarn catching or plucking at that point, resulting not only in non-uniform delivery of the yarn to the machine but also in tangling, stretching and even breaking of the yarn.

50 It had been thought that these disadvantages could be avoided if the conical core were mounted upon a spindle adapted to grip the interior of the conical core and leave a space between the base of the spindle and the bottom of the body of yarn. 55 However, when attempts were made to solve the

problems by the utilization of such a spindle support, an increase in the unwinding difficulties was encountered, due to the fact that upon the unwinding of the outer coils of yarn, the lower inner layers would become loosened and, having no support, they would tend to fall below the base of the cone, with resultant entanglement and breakage. Thus, it is evident that some form of support for the body of yarn is necessary to insure a satisfactory unwinding.

5 Supports having central openings into which the projecting portion of the core fits have been employed with substantially no degree of efficiency. It is, of course, the purpose of such a construction to permit a portion of the weight of the cone to be taken up by contact of the core with the base while the remainder of the weight is transmitted to the support below the yarn body. The primary reason why a device of this nature is not satisfactory is that in no two instances is the portion of the core projecting beyond the yarn body the same length. Accordingly, if the projecting portion is too long, there will be a space between the yarn body and support; or, if the projecting portion is too short, 10 the entire weight of the yarn body will rest on the support.

15 It is, therefore, the object of the present invention to provide an efficient device for supporting packages to be unwound.

20 A further object of this invention is to support packages of strand materials in such a manner as to assure satisfactory unwinding regardless of the variations in length of the projecting core.

25 This invention also contemplates the provision of an adjustable stand for mounting a package thereon in a manner such that the body of strand material will rest lightly on a support.

30 Other objects and advantages will become apparent from the following detailed description when considered in connection with the accompanying drawing wherein the figure represents a cross-section of an adjustable stand having a package of yarn mounted thereon.

35 Referring to the drawing, the numeral 1 indicates an annular disc member provided on its upper surface with a covering 2 of plush, fur, or other suitable material having long pile. Tubular column 3, extending vertically upward from the center of disc 1, is provided with a base portion 4, 40 affixed by any suitable means to the base 5 of the disc 1. The tubular column 3 is provided at its upper end 6 with screw threads 7 for the reception of a set screw 8. The top of the set screw is formed with an enlarged, hemispherical head 45

9, having an opening 10 therein to receive a key 11.

The operation of the supporting mechanism is as follows:

5 A yarn package 12 wound onto a core 13 is placed upright on the support in such a way that the upper end of said core is suspended from the enlarged head 9 of set screw 8. The bottom part 14 of core 13 extends below the level of the yarn package 12 and projects into the opening 15 in the center of the annular disc 1. By inserting the key 11 into the opening 10 the set screw 8 may be adjusted to the proper length so that the yarn package rests lightly on the plush 2 which covers 10 the upper surface of the annular disc. The exact adjustment of the set screw prevents the body 15 of yarn from sinking into the plush and pressing heavily against the support and accordingly, only a portion of the weight of the package is taken 20 up by the plush.

As previously stated, the covering for the annular disc, upon which the body of yarn is to rest, is preferably a material such as plush or fur for the reason that separate fibers project 25 upward from the base material and provide sufficient support to prevent the coils of yarn from sinking downward and becoming tangled, while at the same time offering a minimum of resistance to the coils of yarn withdrawn from the bottom of the yarn body, so that a uniform delivery 30 of yarn to the knitting or other machine is assured. However, any other suitable cover material may be used; for example, the surface of the plate may be covered with soft rubber or 35 horsehair bristles or the like.

It is obvious from the foregoing description that the difficulties heretofore encountered in the setting up of over-end delivery cones are overcome in a simple and effective manner, and that optimum unwinding conditions are quickly obtained 5 with the use of the novel supporting mechanism. While the invention has been particularly described as applied to the support of over-end delivery cones, it may easily be adapted to the support of other types of yarn packages. 10

Having now described the invention in detail in its preferred embodiment, it is to be understood that variations may be made in the constructional details thereof without departing from the spirit of the invention or the scope of the 15 appended claim.

What I claim is:

A device for supporting an over-end delivery cone of strand material comprising a cone core bent inwardly at its upper end, a rigid annular 20 base plate having an opening therein to receive a projecting lower end of the cone core, a resilient plush covering on the upper surface of said base plate adapted to partially support a cone of strand material wound on said core, an adjustable upright member fixed to, and projecting from 25 said base plate and consisting of a tubular column threaded in its upper portion having a set screw therein, said set screw having an enlarged head for partially supporting the core from its top whereby the position of the cone with respect to the base may be regulated at will. 30
